CLAIM

The ornamental design for the inflatable pedal fishing sup, as shown and described.

DESCRIPTION

FIG. 1 is a perspective view of an inflatable pedal fishing sup design showing my new design.

FIG. 2 is a top view of the inflatable pedal fishing sup.

FIG. 3 is a bottom view of the inflatable pedal fishing sup.

FIG. 4 is a left side view of the inflatable pedal fishing sup.

FIG. 5 is a right side view of the inflatable pedal fishing sup.

FIG. 6 is a front view of the inflatable pedal fishing sup; and,

FIG. 7 is a rear view of the inflatable pedal fishing sup.

The broken lines depict portions of the inflatable pedal fishing sup that form no part of the claimed design.
